RECEIVED
UNITED STATES PATENT OFFICE.

THOMAS WILLSON MCKELVY, OF HUMBOLDT, TENNESSEE.

DESIGN FOR A REIN-SUPPORTER.

SPECIFICATION forming part of Design No. 32,494, dated April 10, 1900.

Application filed January 18, 1900. Serial No. 1,938. Term of patent 31 years.

To all whom it may concern:

Be it known that I, THOMAS WILLSON MCKELVY, a citizen of the United States, residing at Humboldt, in the county of Gibson and State of Tennessee, have invented and produced a new and original Design for a Rein-Supporter, of which the following is a specification.

This invention relates to a new and useful design for rein-supporters, and the essential feature resides in upstanding circular eyes continuous with an elongated curved body, which will be more fully hereinafter described.

Figure 1 is a perspective view of a rein-supporter embodying the features of the design. Fig. 2 is a top plan view of the same.

The numeral 1 designates a curved body in the form of an elongated loop open at its up-

per central portion and having curved ends 2 and 3, which are continuous with the top and side members 4 and 5. The inner terminals of the top members 4 are disposed vertically to form straight arms 6 and located on opposite sides or forming the walls of the central upper opening and continued into outwardly-extending circular eyes 7.

Having thus described the invention, what is claimed as new is—

The design for a rein-supporter, herein shown and described.

In testimony that I claim the foregoing as my own I have hereto affixed my signature in the presence of two witnesses.

THOMAS WILLSON MCKELVY.

Witnesses:

LINNIE OVERTON,
W. T. TIPPITT.
